[57] CLAIM

The ornamental design for a animated table top Christmas tree, as shown and described.

DESCRIPTION

FIG. 1 is a perspective view of a animated table top Christmas tree showing our new design with eyes and mouth open; and,

FIG. 2 is a perspective view of a animated table top Christmas tree showing our new design with eyes closed and mouth open.

The broken line showing of the base and the hat are for illustrative purposes only and form no part of the claimed design.
